1.13 : Partial Perspective

1.14 : Partial Perspective

The wheeled suitcase consists of a body equipped with four wheels, a rectangular side handle, and a retractable top handle that extends across the entire width of the body; said body has an essentially parallelepiped shape with rounded corners and comprises two hinged parts or shells of different depths, and a zip fastener; the ends of the zipper are connected to the shells at the same distance from the main shell walls, and gradually move away from the median plane of the body; in the images, the dotted lines represent seams.
